COUNTERBALANCE

Filed Feb. 8, 1927

INVENTOR.
BY J. B. Picard
F. N. Barber
ATTORNEY.

UNITED STATES PATENT OFFICE

JOHN B. PICARD, OF TOLEDO, OHIO, ASSIGNOR TO THE NATIONAL SUPPLY COMPANY,
OF TOLEDO, OHIO, A CORPORATION OF OHIO

COUNTERBALANCE

Application filed February 8, 1927. Serial No. 166,651.

My invention relates to counterbalances, designed particularly for cranks, but they may be applied to other devices.

One object of this invention is to provide a crank with a plurality of counterweights, at least one of which is adjustable about the axial center of a shaft so that the counterweights may assist the crank in counterbalancing loads periodically applied to the crank shaft through a walking beam to a reciprocating pump rod, for example, or so that the counterweights may be adjusted to remove any eccentricity of the mass of the crank and counterweights, as during the operation of a sand reel. Other objects appear hereinafter.

Referring to the accompanying drawings, Fig. 1 is a side elevation of the weights connected together at one side of the shaft; Fig. 2, an end elevation of Fig. 1 with a part broken away; Fig. 3, a side elevation of the upper weight; Fig. 4, a side elevation of the lower weight with a portion broken away; Fig. 5, a section of Fig. 4 on the line 5—5 on Fig. 4; and Fig. 6, a side elevation of the weights partially open.

On the drawing 1 is a shaft to which the weight 2 is keyed and on which the weight 3 is loosely mounted so that it may be turned on the shaft so as to lie at one limit on the same side of the shaft as the weight 2 or so as to lie at the other limit substantially opposite thereto or so as to occupy positions between the said limits. The opposing surfaces of the weights within a small circle around the shaft are reduced in thickness to one-half the thickness of the weights beyond the said circle, whereby recesses 4 and 5 are formed around the shaft at the inner ends of the respective weights 2 and 3. The reduced inner ends of the weights 2 and 3 are marked respectively 6 and 7. The end 6 of the weight 2 lies in the recess 5 in the weight 3, and the end 7 of the weight 3 lies in the recess 4 in the weight 2, so that both weights have the faces thereof which are at right angles to the shaft lying in parallel planes. The reduced inner circular ends or portions 6 and 7 of the weights are provided with holes 8 which may be alined in different angular positions of the

weights from each other, so as to receive bolts 9 by which the weight 3 may be secured to the weight 2. When the movable weight is swung so as to meet the other at one side of the shaft, as in Fig. 1, the weights may be additionally secured together by the bolts 10 passed through the overlapping flanges 11 and 12 on the opposing edges 13 and 14 of the weights 2 and 3.

The weight 2 has near the edge 13 the transverse holes 15, in any one of which the crank pin 16 may be placed. The edge 14 of the weight 3 has the recess 17 to accommodate the end of the crank pin 16 and the nut 18 thereon. That part of the weight 2 which has the holes 15 and the crank pin 16 constitutes a crank member.

The weights 2 and 3 have near their inner ends radial shoulders 19 and 20 which engage and limit their angular movement when they are moved as far as possible from their extreme eccentric positions as shown in Fig. 1, so that the mass of the weights is distributed to remove the eccentricity of the mass. The movable weight may be adjusted to any one of certain angles with the other and secured in that adjustment by placing the bolts 9 in alined holes 8 in the weights. The different angular adjustments provide different eccentricities of the mass of the weights to suit the different conditions to be met.

I claim—

1. The combination of a shaft, a weight keyed thereto, a crank member on the weight, a weight loose on the shaft, and means at the inner ends of the weights for rigidly connecting them together at selected angular relations with each other.

2. The combination of a shaft, a weight keyed thereto, a crank member on the weight, a weight loose on the shaft, and bolts, arranged around the shaft and passed through both weights in a circle around the shaft and near thereto, for securing the weights together.

3. The combination of a shaft, a weight keyed thereto and recessed entirely around the shaft, a weight loose on the shaft and recessed entirely around the shaft, the portion of each weight adjacent to its recess fitting in the

recess in the other weight, and an annular series of bolts passed through the said portions of both weights for securing the weights together whereby the weights may be secured together at selected angular relation with each other.

4. The combination of a shaft, a weight keyed thereto and recessed entirely around the shaft, a weight loose on the shaft and recessed entirely around the shaft, the portion of each weight adjacent to its recess fitting in the recess in the other weight, an annular series of bolts passed through the said portions of both weights for securing the weights together, and additional bolts passed through the edges of both weights when the weights are brought together at maximum eccentricity of their combined mass whereby the weights may be secured together at selected angular relation with each other.

5. The combination of a shaft, a weight keyed thereto and recessed entirely around the shaft, a weight loose on the shaft and recessed entirely around the shaft, the portion of each weight adjacent to its recess fitting in the recess in the other weight, bolts passed through the said portions of both weights for securing the weights together, and additional bolts passed through the edges of both weights when the weights are brought together at maximum eccentricity of their combined mass whereby the weights may be secured together at selected angular relation with each other.

6. The combination of a shaft, a weight keyed thereto and recessed around the shaft, a weight loose on the shaft and recessed around the shaft, the portion of each weight adjacent to its recess fitting in the recess in the other weight, and an annular series of bolts passed through the said portions of both weights for securing the weights together at selected angular relation with each other.

7. The combination of a shaft, a counter-weighted crank member united thereto and having provision for attaching a pitman thereto, a counterweight member loose on the shaft and adjustable angularly around the shaft, and means securing the loose member to the first member at any one of a plurality of angular adjustments therewith.

In testimony whereof, I hereunto affix my signature.

JOHN B. PICARD.
